UNITED STATES PATENT OFFICE.

JOHN STEPHENSON, OF NEW YORK, N. Y.

CAR-TRACK-BRAKE HOUSING.

SPECIFICATION forming part of Letters Patent No. 403,300, dated May 14, 1889.

Application filed July 20, 1888. Serial No. 280,512. (No model.)

To all whom it may concern:

Be it known that I, JOHN STEPHENSON, a citizen of the United States, residing at New York, in the county and State of New York, 5 have invented certain new and useful Improvements in Car-Track-Brake Housings, of which the following is a full, clear, and exact specification.

My invention is a housing for car track-brakes constructed as fully set forth herein-after, and as illustrated in the accompanying drawings, in which—

Figure 1 is a plan of part of a car-truck frame showing my invention. Fig. 2 is a sectional elevation. Fig. 3 is a transverse section.

Necessity for car track-brakes on tramways having inclined planes is now established. Efforts in such constructions have been unsatisfactory, and in many cases of but little use. The service of the track-brake is severe, because the shoes should carry nearly the entire weight of the car and its load moved at a rapid rate and with almost irresistible force by the cable. The shoe is exposed to obstructions from bad joints of the rails, especially at turn-outs, curves, and crossings, and also from uprising pavements in times of frost. These cause derangement of 25 the parts of the brake mechanism the more easily because of the varied location of those parts as attached to different pieces and places of the carriage part or truck, and also the car-body.

35 My purpose is to group the mechanism of the track-brake at each side of the car-body in a housing or receptacle, affording solidity and strength, as also permanence of location to the parts, while affording better protection 40 for the mechanism, with readiness of access and facility for repairs. For this accomplishment I make a housing, 101, of metal, consisting of a rigid frame having a vertical wall-plate, 102, and a horizontal head or ceiling plate, 103, of proper form and dimensions, adapted to the car truck or carriage part at 45 one side of the car to which it is to be fastened. The lower edge of the vertical housing-plate has a ledge, 104, shooting under the truck-sill 5, to prevent the plate from being

forced upward when the weight of the car is on the shoe 100. This vertical plate has also two channel-ways constituting guides 105 for receiving the two vertical or uprising members 90 of the track-shoe to guide the shoe in 55 its vertical motion, and also preserve the shoe from being forced from its position. Near the upper part of the vertical plates are socketed steps 106, fitting to the end journals of the twin rock-shafts 57, which have their other 60 ends journaled in bearings 107 at the verge of the housing head-plate 103. The twin rock-shafts have their arms connected with the track-shoe by articulated bars, which lift and depress the track-shoe at will of the operator 65 and intensify the force of pressure upon the shoe as arms and bars approximate a straight line. An articulated bar unites the arms of the twin rock-shafts, and other two arms of the rock-shafts connected with the shoe by 70 articulated bars. On the verge of the head-plate is a projection, 68, of size and form adapted to limit the motion of the rock-shaft and prevent its arm with the articulated bar from making a straight line, and thus hinder 75 the recoil of the brake. An extended arm, 61, of the rock-shaft has an articulated rod, 62, through which the energy of the operator is conducted to the brake. The vertical plate and the ceiling-plate have holes to receive 80 the bolts 109, by which or other known method the housing may be fastened to the car-truck. Thus the complete mechanism of the brake is housed and in condition to be attached to to or removed from a car as need requires. 85

I do not here claim the construction of the brake-shoe and its connections, as the same constitutes the subject of separate applications for Letters Patent, Serial Nos. 280,510 and 280,511. 90

I claim—

1. A track-brake housing consisting of a rigid frame secured to the car truck or carriage at one side of the car and constructed with bearings for horizontal rock-shafts, and 95 with vertical guides to support the working parts of the car track-brake, substantially as and for the purpose described.

2. A track-brake housing having vertical guides adapted to vertical members of the 100

- track-shoe to control the motion thereof, and with a vertical wall with sockets or bearings for the ends of horizontal rock-shafts, substantially as and for the purpose described.
- 5 3. A track-brake housing having at the under side of its head-plate one or more rock-shaft journal-bearings for horizontal rock-shafts, substantially as and for the purpose described.
- 10 4. A track-brake housing with bearings for twin rock-shafts having arms with articulated bars coupled to the shoe, substantially as and for the purpose described.
- 15 5. A track-brake housing having bearings for a rock-shaft, and having a stop adapted to limit the revolution of the rock-shaft, substantially as and for the purpose described.
- 20 6. A track-brake housing supporting a rock-shaft united to the brake-shoe by an articulated bar, and an arm of the rock-shaft with an articulated bar connected with the hand-lever and adapted to convey the energy of the operator to the brake mechanism, substantially as and for the purpose described.
- 25 7. A track-brake housing supporting a track-shoe with two articulated bars connecting the shoe with twin rock-shafts united by an articulated bar, and each rock-shaft having its two journals in bearings in the housing-walls, one of the rock-shaft arms connected with a rod capable of conducting the energy of the brake-operator to the track-shoe, substantially as and for the purpose described.
8. A track-brake housing with shaft-bearings and guides holding in assemblage the mechanism of a brake and constructed for attachment to the car, substantially as and for the purpose described.
9. A track-brake housing having on its rear wall guides for vertical members of the track-shoe, substantially as and for the purpose described.

In testimony whereof I have signed my name to this specification in the presence of two subscribing witnesses.

JOHN STEPHENSON.
